[57] CLAIM

The ornamental design for a combined retaining and dispensing rack for food containers or the like, substantially as shown and described.

DESCRIPTION

FIG. 1 is a perspective view of a combined retaining and dispensing rack for food containers or the like showing our new design;

FIG. 2 is a front elevational view thereof;

FIG. 3 is a side elevational view thereof;

FIG. 4 is a top plan view thereof;

FIG. 5 is a bottom plan view thereof; and

FIG. 6 is a rear elevational view thereof.
